US0D1063944S

(12) **United States Design Patent** (10) **Patent No.:** **US D1,063,944 S**
(45) **Date of Patent:** **** Feb. 25, 2025**

(54) **HOUSING MODULE FOR AN ELECTRONIC DEVICE**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Daniele De Iuliis**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Joe Sung Ho Tan**, Vienna (AT); **Clement Tissandier**, San Francisco, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/833,453**

(22) Filed: **Apr. 4, 2022**

Related U.S. Application Data

(63) Continuation of application No. 29/802,000, filed on Aug. 2, 2021, now Pat. No. Des. 947,853, which is a

continuation of application No. 29/749,438, filed on Sep. 4, 2020, now Pat. No. Des. 926,768, which is a continuation of application No. 29/691,815, filed on May 20, 2019, now Pat. No. Des. 895,628, which is a continuation of application No. 29/655,032, filed on Jun. 29, 2018, now Pat. No. Des. 849,010, which is a continuation of application No. 29/612,835, filed on Aug. 4, 2017, now Pat. No. Des. 848,999.
